UNITED STATES PATENT OFFICE

FRED WAITE, OF INGLEWOOD, OTLEY, ENGLAND

WIPING AND SCRAPING MECHANISM OF INTAGLIO MACHINES

Application filed December 19, 1928, Serial No. 327,061, and in Great Britain December 20, 1927.

This invention relates to wiping mechanism (and parts in connection therewith) that is used in die-stamping and plate printing machines which have metal blades for 5 shaving or removing the excess of ink from the printing surface, and particularly to that type wherein the wiping member has a curved surface which presses the wiping paper against the said printing surface and which 10 is rocked as the die is being wiped by it, while it is held clear of the die as this is returning (after imparting its impression) to the end or position where it is inked.

To permit the rocking actions of the wiping member, this member has its leading end pivoted upon spring-actuated rods. The springs which are mounted on said rods have their lower ends resting upon supports through which the ends of the rods may 20 slide, while upon said rods adjustable collars are fixed and arranged to press against the other ends of the springs in order to enable the springs to force the wiping member against the die.

25 Heretofore the supports for the lower ends of the springs have been fixed or stationary so that their pressure upon the wiping member has increased as this member has been rocked from where its leading end is in contact with the die until its rear end is brought to press thereon.

By these actions the pressure springs upon the supporting rods have been compressed through the whole space that the rocking 35 movement has carried the leading end of the wiping member because the collars fixed on the pivoted rods have been pressed upon the upper ends of the springs while the lower ends of said springs were held against movement. This great pressure has caused excessive wear of the operating cams as well as requiring considerable power to carry out the said function.

40 My present invention consists in the application of means whereby I am enabled to

control said spring pressure and cause same to remain uniform through the whole rocking and wiping movements of the wiping member, and to increase or decrease or otherwise vary said pressure as I may find desirable or 50 advantageous. The devices which I employ also enables me to entirely suspend the actions of the wiping member when the printing surface does not require any other preparation than the mere scraping away of the superfluous ink to prepare said surface to give the desired impressions.

The bearings which carry the scraping blade above referred to are made interchangeable with those that carry a shaving blade 60 that I use in conjunction with the wiping-members, and are the only parts which are to detach from and apply to the machine when changing from photogravure printing to die-stamping, since the other sets of parts which 65 act in conjunction with the two separate kinds of blades occupy their respective positions without interfering with each other.

In order that my said invention may be 70 readily understood, I have hereunto appended sheets of drawings illustrative thereof to which by figures and letters reference is made in the following description:

Fig. 1 is a side elevation of sufficient of the 75 wiping mechanism of a printing machine to show the application of our improved devices. In this view the wiping member and its operating parts are shown in the positions which they occupy when the wiping operations are finished.

Fig. 2 is a similar view to Fig. 1 but shows the several positions of the different devices assumed at the commencement of the wiping actions.

Fig. 3 is a view of the parts shown by Figs. 1 and 2 as seen looking from right to left of said figures.

Fig. 4 is a similar view to Fig. 2 but shows certain of the parts separately from the other 80

parts in order that same may be clearly understood.

Fig. 5 is a view of the part's shown by Fig. 4 as seen looking from right to left of said figure.

Figs. 6 and 7 are similar views to Figs. 2 and 3 respectively but show modifications hereinafter described.

Fig. 8 is a similar view to Fig. 6 but shows only part of the devices in said former figure.

Fig. 9 is a similar view to Figs. 2 and 1 but shows connections for operating the front edge of the wiping member.

Fig. 10 is an end elevation of the parts shown by Fig. 9 as seen from left to right of said figure.

Fig. 11 is a side elevation of the devices made use of for giving the tilting action to the wiping member.

Fig. 12 is an end elevation of the parts shown by Fig. 11 as seen looking from right to left of said figure.

Figs 13 and 14 are end elevations respectively showing our arrangements of scraping and shaving devices which may be readily fixed in position when the wiping mechanism is placed out of action.

In the several sheets of drawings 2 and 2^a indicate the end frames of the machine and 3 the wiping member.

To attain the object of my invention I arrange the lower ends 4^a of the springs 4, which are mounted upon the rods 5, to be supported by the extending ends 6^a of the cam-actuated-levers 6. As shown by Figs. 1, 2, 3, 4 and 5 the supporting of the springs 4 by the ends 6^a of the levers 6 is carried out by the employment of sleeves 7 which are arranged to enable or permit the ends of the rods 5 to 40 slide within them.

The ends 6^a of the levers 6 are bifurcated so that they span a part 7^a which is flattened and extends beyond the lower end of the sleeve 7 in order to take between the bifurcations 6^a of said levers 6. Or instead of making use of the sleeves 7 I make use of a swivelling bracket or member 7^b which is pivoted to oscillate, upon the end 6^c of the lever 6^b, as shown by Figs. 6 and 7, in which case the lower end 4^a of the spring 4 rests upon the swivelling bracket 7^b while the end of the rod 4 passes through said bracket during the compressing of the spring 4 when the wiping member 3 is being oscillated from its position shown by Figs. 2 and 4.

In the arrangement shown by Figs. 1 to 5, the rods 5 are guided through the brackets or bearings 8 while in the latter arrangement shown by Figs. 6 and 7 this bracket 8 for guiding the rods 5 may be dispensed with or may be arranged to swivel as may be found advantageous.

The rods 5 are the spring actuated rods which are pivoted at 5^a to the leading edge 65 of the wiping-member 3

The levers 6 (or 6^b) are fixed upon a shaft 9 which extends crosswise the machine from the frame side 2 to the frame side 2^a upon which it is mounted to oscillate. On this shaft 9 is loosely mounted a lever 10 carrying a bowl or runner 10^a for contact with an operating cam 11 which cam is fixed upon a rotary shaft 12 which is preferably the shaft upon which other cams are mounted for giving the rocking motion to the wiping member 3 as is hereinafter described.

The lever 10 carrying the bowl 10^a has also a pawl 12 pivoted upon it at 10^b (preferably co-axially with the bowl 10^a) and this pawl 12 is for engagement with an appropriately shaped engaging surface 13^a formed on a lever 13 that is fixed upon the shaft 9 upon which the lever 10 is loosely mounted. By these means when the lever 13 is actuated by the pawl 12, as hereinafter explained the shaft 9 upon which the lever 13 is fixed will be oscillated by said lever 10 when it is moved by the actions of the cam 11 to carry its pawl 12 forward to engage with and move the lever 13 in order to oscillate the shaft 9.

Since the levers 6 (or 6^b) are fixed upon the shaft 9 the said oscillating motions of said shaft 9 cause the said levers 6 (and 6^b) also to oscillate so that their outer ends will commence to press upon the springs 4 and thus will raise or tend to raise the rods 5 and therefore the rear edge of the wiping member 3 into its operation position because said springs 4 have their upper ends 4^b held against sliding over the rods 5 by means of loops 5^c which are fixed upon said rods 5 for said springs to press against.

From this arrangement of the said devices, in accordance with the shape or formation of the cam 11, so will the ends of the levers 6 move over the rods 5 to press the springs 4 more or less as we may form the cam 11 so to do. The formation of the cam is of such a character as will meet the requirements of the movements of the wiping-member 3 to cause said wiping-member to be pressed with the desired pressure of the springs 4 into contact with the surface 14 which has to be wiped, while during the rocking actions of said member 3 from the position shown in Fig. 1 to the position shown in Fig. 2 the said desired compression of the springs is provided for in order to be maintained even or as desired by the cam 11 permitting the lowering or receding of the ends of the levers 6 and 6^b 110 to be carried out in accordance with the receding actions or lowering movements of the leading edge of the wiping member 3.

The lever 13 which is fixed upon the shaft 9 and which is actuated by the advancing of the pawl 12, is arranged so as not to follow the pawl lever 10 through its full movement towards the bottom of the cam 11 as shown by Figs. 2 and 4 for the purpose hereinafter explained. This arresting of the lever 13 is 130

effected by the levers 6 being arrested by adjustable screws 15 fixed upon the side frames 2 and 2a lying in the path of motion of the lever 6 (or 6b) in order to act as stop pieces for said lever 6 (or 6b).

The arresting of the levers 6 and 6b in the positions described, and which are in the lowest positions to which they have moved in order to relieve their pressure on the springs 4, enable the lever 10 in following its cam 11 to carry the pawl 12 clear of the end 13a of the lever 13 as is shown by Figs. 2 and 4.

When the pawl lever 10 is in this position the cam 16 has reached its highest position (Fig. 11) and in doing so it has raised a lever 17 which has its outer end 17a formed of the curved character shown so as to lift the pawl 12 out of the path of motion of the lever 13 at which time the actions of the wiping member 3 are entirely suspended.

The runner 10a on the lever 10 is kept in contact with the cam 11 by the recoil of the spring 10d.

To enable the cam 16 to raise the lever 17, it actuates the runner 21a which is carried by the lever 21 so that in so doing it oscillates the shaft 19 upon which it is fixed. In thus oscillating the shaft 19 the lever 18 is also oscillated and by engaging the lever 17 raises this as above stated.

The actions of the cam 16 also effect or bring about the rocking motion of the wiping-member 3 by means of a lever 20 being fixed upon the shaft 19 which is oscillated by said cam 16. This lever 20 is connected by a rod 23 to a lever 24 fixed upon a cross shaft 25 so that by another lever 24a, also fixed thereon, being connected by another rod 26 to the arm 27, fixed to the wiping member 3, the said rocking actions are carried out in the usual and well known manner.

When the wiping-member 3 is in use I employ in connection therewith, my well known shaving blade 30 (see Figs. 6 and 14) for clearing away the excess of ink from the printing surface 14 before the wiper commences its actions. In thus making use of my said blade 30 I arrange same to have its bearings or supporting members 31 to be carried by brackets 32 which have their engaging surfaces *a* and *b* formed to receive and retain same by the employment of a single fixing screw 33 at each end thereon, thus the removal of said blade 30 as well as its replacement in position is readily and quickly effected.

When the wiping mechanism is thrown out of use (as when photogravure printing is being carried out) and a scraping blade instead of the shaving blade 30 is required, I then arrange said scraping blade 30a (see Fig. 13) to have its supporting members 31a shaped to fit the same engaging surfaces *a* and *b* on the brackets 32 so that the same fix-

screws 33 will secure them in position. In this case I use the same operating rod 34 (for actuating which the usual and well known devices are employed) for actuating the scraping blade 30a that is used in the other case for actuating the shaving blade 30, the only difference being the addition of a lateral arm 35 to the rod 34 (as is shown by Fig. 13) to enable same to actuate the blade 30a in the reverse direction to that of the blade 30. Any suitable connection may be provided between the arm 35 and the scraping blade 30a to enable the movements of said arm by the rod 34 to cause the operation of the scraping blade 30a.

To suspend the actions of the wiper 3 for the purpose above stated we arrange a pawl 28 which is pivoted upon the framework 2 so that it may engage with an extension 20a formed on the outer end of the lever 20 in which position it will hold said lever 20 as shown by Fig. 11 so that the lever 21 will be retained from following the actions of the cam 16.

The adjusting of the pawl 28 in the position stated is effected by the attendant actuating the hand lever 29 so that it will move the connecting rod 29a into the position shown by Fig. 11 in order to enable this rod 29a to place the catch 28 into the position stated. When the catch 28 is retaining the lever 20 as stated it retains also the shaft 19 in position for enabling the lever 18 to raise the lever 17 by which means the engaging end 17a of the said lever 17 will raise the pawl 12 clear of the end 13a of the lever 13 as is hereinbefore explained.

In connection with the mechanism hereinbefore described for operating the wiping member 3 I make use of the usual cam actuated rods 36 for operating the opposite or following edge of the said member 3 to that actuated by the rods 5. These rods 36 are actuated by levers 37 engaging springs 38 mounted upon said rods 36, and these levers are fixed upon a cross shaft 39 which is caused to oscillate by a lever 40, fixed thereon, having its runner 40a in engagement with a cam 41 fixed upon the shaft 12.

It is obvious that instead of making use of open spiral springs 4 as shown by the several drawings I may arrange to make use of closed spiral springs by the addition of parts required for bringing such springs into action.

Such being the nature of my invention what I claim is:—

1. In wiping mechanism for printing machines, means for removing the excess of ink from the printing surface, a wiping member, supporting rods pivotally connected to the leading and rear edges of said member, a spring for acting upon each of said rods, levers for pressing upon said springs, shafts upon which the levers are fixed, other levers

fixed on said shafts, a cam for actuating the lever and its shaft for effecting pressure on the rear edge of the wiping member, an engaging member operating in connection with the lever fixed upon the shaft for pressing upon the leading edge of the wiping member, a lever loosely mounted upon said shaft and arranged to actuate the engaging member operating with the lever fixed upon the said shaft, and a cam for actuating the loosely mounted lever.

2. In wiping mechanism for printing machines, means for removing the excess of ink from the printing surface, a wiping member, supporting rods pivotally connected to the leading and rear edges of said member, a spring for acting upon each of said rods, levers for pressing upon said springs, shafts upon which the levers are fixed, other levers fixed on said shafts, a cam for actuating the lever and its shaft for effecting the pressure on the rear edge of the wiping member, an engaging member operating in connection with the lever fixed upon the shaft for pressing upon the leading edge of the wiping member, a lever loosely mounted upon said shaft and arranged to actuate the engaging member operating with the lever fixed upon the said shaft, a cam for actuating the loosely mounted lever, and lever and cam devices for effecting the rocking movements of the wiping member.

3. In wiping mechanism for printing machines, means for removing the excess of ink from the printing surface, a wiping member, supporting rods pivotally connected to the leading and rear edges of said member, a spring for acting upon each of said rods, levers for pressing upon said springs, shafts upon which the levers are fixed, other levers fixed on said shafts, a cam for actuating the lever and its shaft for effecting the pressure on the rear edge of the wiping member, an engaging member operating in connection with the lever fixed upon the shaft for pressing upon the leading edge of the wiping member, a lever loosely mounted upon said shaft and arranged to actuate the engaging member operating with the lever fixed upon the said shaft, a cam for actuating the loosely mounted lever, lever and cam devices for effecting the rocking movements of the wiping member, a lever fixed upon the shaft which is oscillated by the cam that effects the rocking movements of the wiping member and a lever loosely mounted on the said shaft and actuated by the lever which is fixed thereon to control the engaging member through which motion is transmitted to the leading pair of springs.

4. In wiping mechanism for printing machines, means for removing the excess of ink from the printing surface, a wiping member, supporting rods pivotally connected to the leading and rear edges of said member, a

spring for acting upon each of said rods, a lever for pressing upon each of said springs, shafts upon which the levers are fixed, other levers fixed on said shafts, a cam for actuating the lever and its shaft for effecting the pressure on the rear edge of the wiping member, an engaging member operating in connection with the lever fixed upon the shaft for pressing upon the leading edge of the wiping member, a lever loosely mounted upon said shaft and arranged to actuate the engaging member operating with the lever fixed upon the said shaft, a cam for actuating the loosely mounted lever, lever and cam devices for effecting the rocking movements of the wiping members, a pawl for engaging an extension from the lever which effects the rocking actions of the wiping member in order to suspend its movements and therefore to check or suspend the action of the feed, a connecting rod pivoted to said pawl and a hand lever for actuating said rod to effect the said engagement of the pawl.

5. In wiping mechanism for printing machines, means for removing the excess of ink from the printing surface, a wiping member, supporting rods pivotally connected to the leading and rear edges of said member, a spring for acting upon each of said rods, a lever for pressing upon said spring, shafts upon which the levers are fixed, other levers fixed on said shafts, a cam for actuating the lever and its shaft for effecting the pressure on the rear edge of the wiping member, an engaging member operating in connection with the lever fixed upon the shaft for pressing upon the leading edge of the wiping member, a lever loosely mounted upon said shaft and arranged to actuate the engaging member operating with the lever fixed upon the said shaft, a cam for actuating the loosely mounted lever, lever and cam devices for effecting the rocking movements of the wiping member, a lever fixed upon the shaft which is oscillated by the cam that effects the rocking movements of the wiping member, a lever loosely mounted on the said shaft and actuated by the lever which is fixed thereon to control the engaging member through which motion is transmitted to the leading edge of the wiping member, a pawl for engaging an extension from the lever which effects the rocking actions of the wiping member in order to suspend said actions and therefore to check or arrest the actions of the wiping member, a connecting rod pivoted to said pawl and a hand lever for actuating said rod to effect the said engagement of the pawl.

6. In combination with wiping mechanism for printing machines, a blade for removing the excess of ink from the printing surface, devices for operating said blade, a wiping member, supporting rods pivotally connected to said member, springs for acting

upon said rods, levers for pressing upon said springs, shafts upon which the levers are fixed, other levers fixed on said shafts, a cam for actuating the lever and its shaft for effecting the pressure on the rear edge of the wiping member, an engaging member operating in connection with the lever fixed upon the shaft for pressing upon the leading edge of the wiping member, a lever loosely mounted upon said shaft and arranged to actuate the engaging member operating with the lever fixed upon the said shaft, and a cam for actuating the loosely mounted lever.
